UNITED STATES PATENT OFFICE.

PAUL STELLMACH, OF BROOKLYN, NEW YORK.

PAPER FASTENER.

Application filed December 30, 1926. Serial No. 157,977.

This invention relates to improvements in paper fasteners, loose-leaf binders, and the like, and has particular reference to such devices which embody tongues which are 5 adapted to be folded over on a clamping plate after passing through the papers to be secured.

Heretofore, similar fasteners have included a base plate initially formed with 10 tongues of reduced width extending outwardly from its ends. The production of such devices have necessarily involved considerable wastage of metal stock, and it is an object of the present invention to reduce 15 such scrap or waste to a minimum.

Another object is to provide such a device with a base which will be especially strong yet light in weight, and exceedingly compact for purposes of storage and shipment.

20 Another object is to provide such a device with a plurality of tongues arranged in pairs whereby a more secure fastening will be effected.

Another object is to provide such a device 25 which will be simple in construction, economical in manufacture, convenient for use, and a substantial improvement in the art.

Other objects and advantages will readily 30 appear from the following description when taken in connection with the accompanying drawings, wherein one form of the invention is shown by way of illustration and whereir. Figure 1 is a top plan view of the body of the improved paper fastener in condition for packaging;

35 Figure 2 is a similar view of one form of clamping plate which may preferably be employed in conjunction with the improved fastener;

40 Figure 3 is a longitudinal, sectional view on line 3—3 of Figure 1;

Figure 4 is a similar view showing the paper engaging tongues bent outwardly from the base, in condition for insertion through 45 a plurality of sheets of paper or the like;

Figure 5 is a similar sectional view through the complete fastener and clamping plate, in association with the papers held together; and

50 Figure 6 is a detail perspective view of the two parts which make up the body of the improved fastener and showing said two parts separated as immediately prior to their assembly.

55 The improved paper fastener of the present invention includes a main body portion

10, with which is preferably employed a clamping plate 11, the papers or the like to be fastened together being disposed between said body portion and clamping plate. 60 Preferably the body portion 10 is formed of a double thickness of ductile sheet material and has been shown in the drawings as including a pair of superimposed plates 12 and 13 which are of substantially rectangular outline and similar to each other in all respects. When the fastener is in condition for use it has a plurality of tongues which extend substantially at right angles to the plane of the base plates 12 and 13, said 65 tongues being arranged in co-extensive pairs intermediate the ends of said plates. For example, as best shown in Figs. 4 and 6, a pair of tongues 14 and 15 extend upwardly from the base adjacent one end thereof, 70 while similar tongues 16 and 17 extend in the same direction adjacent the other end of the base. In order that the device may be manufactured with a minimum amount 75 of waste in material, the tongues 14 to 17, inclusive, are integral with the base plates and deflected upwardly therefrom in such a manner as to leave a substantially central perforation 18. It follows from this that 80 the tongues are of less width than the base plates, and of course the proportions may be varied as desired to suit requirements of the trade.

The clamping plate 11 is also preferably 85 formed of sheet metal or other suitable stiff material whereby to reinforce the papers which are bound together, and is provided adjacent its opposite ends with preferably 90 rectangular apertures 19 and 20 which are spaced apart a distance equal to the distance 95 between the pairs of co-extensive tongues. In the use of the device the tongues 14, 15 and 16, 17 are projected through a plurality 100 of sheets of paper A, as shown in Fig. 5, after which the clamping plate 11 is applied, 105 said tongues passing through the respective apertures 19 and 20. When the clamping plate 11 then comes to rest on top of the papers A, the tongues 14 and 15 may be bent 110 away from each other in such a manner as to overlie the clamping plate and the papers, and similarly the tongues 16 and 17 may be bent away from each other for the same purpose. It will be obvious that this construction provides a particularly advantageous paper fastener, in that there is practically no possibility for the deflected

tongues to become loose thereby impairing the utility of the device. If desired, the clamping plate 11 may be provided with either stationary or adjustable means for 5 anchoring the ends of the tongues, such means being well known to those skilled in the art and capable of being very easily applied to the present fastener. In that case, it might of course be desirable to form the 10 clamping plate 11 of greater length than the base plates 12 and 13.

By way of reinforcing the base plates 12 and 13 in order to compensate for the removed material from the perforation 18, the 15 said base plates are preferably formed with longitudinal ribs 21 which extend between the side edges of the base plates and at opposite sides of said perforation 18. Said ribs 21 can best be formed by embossing 20 dies, and the result is that such ribs on the lower plate 13 will fit into corresponding grooves on the lower side of the plate 12 whereby to cooperate in holding the said 25 plates against lateral movement with respect to each other. The tongues 14, 15, 16 and 17 can very easily be defined in outline by a punching operation, which in fact provides the base plates with an H-shaped slit 22, and preferably the cross-slit 23 is spaced to 30 one side of the transverse center of the plate in such a manner that the tongues 14 and 16 will be longer than the tongues 15 and 17. Such a difference in length is usually provided in order that the tongues may be more 35 easily bent away from each other after being passed through the papers to be held together, and with this construction the superimposed plates 12 and 13 are identical in detail, with the exception that said cross-slit 23 in one plate is disposed to the right of the transverse center, while in the other plate it is disposed to the left of the center. In other words, they are staggered. In order 40 to more firmly secure the base plates 12 and 13 together, any suitable fastening means may be employed. For example, they have been illustrated in the drawings as provided at their opposite ends with reversely bent ears 24 which are formed from three-sided 45 perforations 25 and bent down against the upper surface of the plate 12. It is to be understood that the thickness of the material 50 has necessarily been exaggerated in the

drawings, and that with the thin stock from which the improved paper fastener is formed 55 said ears 24 may be provided without forming any undesirable roughness or projection for contacting the lowermost paper.

From the foregoing, it will be evident that a substantial advance has been made in the 60 art by providing a paper fastener which will give a more secure binding than prior art devices, and which can be manufactured at considerably lower cost. Since the paper engaging tongues are formed from deflected 65 portions of the base member, and as they are not necessarily deflected until they are desired for use, such paper fasteners can be packed much more conveniently than those in which the tongues are initially deflected 70 from their bases. Obviously, the invention is susceptible of numerous modifications in the details of construction and arrangement of parts, and the right is herein reserved to make such changes as fall within the scope 75 of the appended claims without departing from the spirit of the invention.

Having thus described my invention, what I claim is:

1. A paper fastener formed of a pair of 80 superimposed sheets of ductile material forming a base, and a pair of co-extensive tongues deflected outwardly from a perforated portion of the base.

2. A paper fastener having a base member 85 formed of a double thickness of ductile sheet metal, and having a plurality of tongues arranged in spaced apart co-extensive pairs, the tongues being of less width than the base and being deflected outwardly therefrom 90 leaving a perforation.

3. In a paper fastener, in combination, a base member formed of a double thickness of ductile sheet material, a plurality of tongues extending at right angles to the plane 95 of the base member and adapted to be passed through the papers to be fastened, and a clamping plate adapted to overlie the paper, the clamping plate being slotted for the passage of said tongues, and the tongues being arranged in co-extensive pairs, the individual tongues of each pair being adapted 100 to be bent in opposite directions on the outer side of the clamping plate.

PAUL STELLMACH.
